UNITED STATES PATENT OFFICE.

ARTHUR CLARKE SARGEANT, OF AGAWAM, MASSACHUSETTS.

DOOR-STOP.

1,352,147.

Specification of Letters Patent. Patented Sept. 7, 1920.

Application filed May 13, 1919. Serial No. 296,773.

To all whom it may concern:

Be it known that I, ARTHUR CLARKE SARGEANT, a citizen of the United States of America, residing at Agawam, in the county 5 of Hampden and State of Massachusetts, have invented a new and useful Door-Stop, of which the following is a specification.

My invention relates to devices for holding doors in open position, and consists essentially of a fixed member carried by the door and a movable member supported from a member of the door frame or casing, both of special and peculiar construction, together with such other parts and members 15 as may be necessary or desirable in order to render the device complete and serviceable, all as hereinafter set forth.

The primary object of my invention is to provide a stop, of the class described, which 20 is applicable for use in connection with any swinging door at the top, where it is out of the way, and capable of securing the door when open and holding the same in such position, such stop being readily attached, 25 automatic in both the engaging and releasing operations if desired, strong and durable, convenient, and withal entirely practicable and highly efficient.

Another object is to produce such a stop 30 which may be set so as to be releasable only by hand.

Still another object is to provide a latch that can be used with a door that has no spring, or, in other words, with a door that 35 is not self-closing.

Other objects and advantages will appear in the course of the following description.

I attain the objects and secure the advantages of my invention by the means illustrated in the accompanying drawings, in which—

Figure 1 is a top plan of a practical form of my invention, the stop members being applied to a door casing and door, which latter is closed; Fig. 2, a front elevation of the parts and members disposed as in the first view; Fig. 3, a front elevation of said parts and members, said door being open and under restraint from the stop; Fig. 4, a 45 side elevation of said door and stop as disposed in the preceding view, and as viewed from the right-hand side of such view; Fig. 5, a similar side elevation, but showing the stop-engaging members unlocked and about 50 to be separated entirely by the closing of the door; Fig. 6, an enlarged, top plan of the stop member which is attached directly

to the door; Fig. 7, an enlarged, bottom plan of the swinging stop member, and, Fig. 8, a detail in section of a bumper that may 60 be used in the event the door be not provided with self-closing means.

Similar reference characters designate similar parts throughout the several views.

In the general views fragmentary portions of a door jamb, a door lintel, and a door are represented at 1, 2, and 3, respectively. An arm 4 is secured by screws or otherwise to the underside of the lintel 2, being let into said lintel in this case, and in 70 order to show such arm in full and the top of the door 3 the lintel, which is over the attached end of said arm and over said door when closed, is represented by broken lines in Fig. 1, so as to disclose in full the parts 75 that otherwise would be hidden. The jamb and lintel are both shown in section in Figs. 4 and 5. In the last view the fragment of the door 3 therein appearing is in section.

A spring hinge of ordinary construction 80 is represented at 5. This hinge, with its companion or companions which are not shown, supports the door 3 from the jamb 1, and has a constant tendency to swing said door into closed position and hold it shut. 85

The stop comprises, with the arm 4, which is rigidly attached at its inner or rear end to the lintel 2, as previously observed, a freely-suspended, swinging latch 6, at the forward end of said arm, and a 90 bracket 7 having a lug 8, said bracket being rigidly attached, by screws or other means, to the inside of the door 3, or to the side of said door which is adjacent to the arm. In addition to these parts and members, the 95 arm 4 is provided, back of the latch 6, with a depending lug 9, and there is a bumper 10 which projects from the same side of the door 3 to which the bracket 7 is secured.

The arm 4 has a vertical lug 11 at the 100 outer or foremost end, which is flush with the outer edge of said arm, and the upper part or head of the latch 6 is pivotally connected with said lug by means of a bolt 12 and a nut 13, a washer 14 being interposed 105 between said latch head and the head of said bolt. The center of gravity of the latch 6 being through the center thereof and through the bolt 11, said latch normally hangs vertically, and upon slight pressure 110 or the application of very little force the latch is swung forwardly or rearwardly, to return to the vertical as soon as such pressure or force is removed. The lug 9 de-

pends from the same edge of the arm 4 to which the latch 6 is contiguous.

The latch 6 has an arcuate, bottom edge 15, concentric with the bolt 11, and depending from such edge is a keeper 16. The keeper 16 extends obliquely across the central portion of the edge or bottom 15, from the left-hand side forward and over to right-hand side of such bottom, and has a notch 17 in what may be termed its front end. The sides of the keeper are slightly convex. One side (18) of the notch 17 is short and extends from the outer side of the latch 6 or the outer, longitudinal edge of its bottom 15 inwardly a short distance, and the other side (19) of said notch is longer and extends forwardly, from said first-named side, toward the front end of said latch or of said bottom. Preferably the sides 18 and 19 form an acute angle with each other. The oblique sides of the keeper 16 are designated by the numerals 20 and 21, the former extending from the front end of the notch side 19, rearwardly and inwardly to the inner side of the latch 6, where said side 20 joins the side (24) of said keeper that is a continuation of said inner latch side; and the latter extending rearwardly, from the outer end of the notch side 18, and inwardly to the rear end of said keeper side 24. The side 21 is, therefore, longer than the side 20, but shorter than the combined lengths of the sides 24 and 20.

The lug 8 rises from the horizontal part 35 of the bracket 7, at the forward or outer end thereof, and said lug is in plan a parallelogram placed on said horizontal part of said bracket with its ends (22-22) approximately at right-angles to the door 3, and its sides (23-23) inclined inwardly toward the hinged edge of said door. The elevation of the top of the lug 8 is just low enough to clear the latch bottom 15, when the door 3 is swung open, and the relative location of said lug is such that at such time said lug is moved through an arcuate course which is intersected by the keeper 16, and consequently encounters the latter.

The lug 9 is in the path of the bumper 10 when the door is opened. The bumper 10 is adjustable in and out, for the reason presently to be given, and to that end said bumper may consist of a screw.

The operation of this door stop is described as follows:

When the door 3 is opened sufficiently wide, on and against the force of the spring hinge 5, the outer side 23 of the lug 8 encounters first the side 20 of the keeper 16, and, by reason of such contact and as said door continues to move, the latch 6 is caused to swing rearwardly on the bolt or pivot 12 until said lug passes by the extreme front end of said keeper, when said latch swings 65 forward by gravity and the contacting end,

which is now the rear end, of said lug is received in the notch 17. The door is now released to the spring hinge 5, and at once causes the inner side 23 of the lug 8 to come into engagement with the side 19 of the notch 17—see Figs. 3 and 4. The door is thus held by the latch 6, through the medium of the lug 8, and prevented from closing.

A little care must be exercised in engaging the parts not to push the door open far enough to carry the lug 8 entirely beyond the keeper, or so far that, when the latch 6 swings forward, said lug will not be received in the notch 17. In the event this be done, however, it is necessary simply to manipulate the door in the manner explained below for unlocking, and then bring about the locking action just as explained above.

To unlock or release the door 3, push it open farther to cause the lug 8 to pass out of the notch 17 and beyond the keeper 16. It is to be understood that, while the latch and lug are in locking engagement, the former is disposed rearwardly so that it will swing forward as soon as the same is released by the lug. The latch, therefore, swings forward and the parts are disposed as represented in Fig. 5. Now permit the door to close. As the door swings toward its opening, the inner side 23 of the lug 8 encounters the side 21 of the keeper 16 and crowds said keeper out of the way by causing the latch 6 to be swung forward until the outer end 22 of said lug passes clear of said side 21 and said lug clear of said latch. The latch at once assumes its normal position in readiness to be engaged by the lug 8 and to lock the door the next time the same is opened.

The primary purpose of the lug 9 and bumper 10 is to protect the latch 6 from the shock or strain that would be experienced thereby, in the absence of some such means of protection, in the event the door 3 be opened violently or pressed too hard against said latch. To this end the bumper is set out only far enough to encounter the lug 9 just before the door reaches the latch 6, there being plenty of clearance between said bumper and lug to enable the lug 8 to become interlocked with the keeper 16, when said door is opened, and to be released therefrom and swing clear thereof, when said door is swung inwardly to close it.

Sometimes it is desired that the door shall be unlocked by hand, or, in other words, by manually swinging the latch 6 rearwardly out of engagement with the lug 8. This result is obtained by setting the bumper 10 out far enough to encounter the lug 9 directly the lug 8 enters the notch 17, so that the door can not be pushed open any farther or far enough to take said lug out of said notch, and it becomes necessary to reach up

105

with the hand and swing said latch back in order to release the door. No spring is required in this case.

In the absence of spring hinges or equivalent elements, a resilient bumper may be employed, such as that illustrated in Fig. 8, for example. This bumper consists of a cap 25, which is provided with a screw 26 for attachment to the door, a spiral spring 27 within such cap, and a pin 28 that protrudes from said cap at the front end, and has a head 29 within said cap, against which said head bears.

The parts are so proportioned that, when the resilient bumper is substituted for the bumper 10, the pin 28 is forced inwardly, against the resiliency of the spring 27, by means of the contact of said pin with the lug 9, when the lug 8 and the keeper 16 become engaged, and while such engagement lasts. The spring 27 has a tendency to swing the door in the direction to close it, just as do the spring hinges, and so causes the lug 8 to be retained in contact with the side 19 of the notch 17, during the time of interlocking engagement of the parts.

The resilient bumper may, like the bumper 10, prevent the door 3 from coming into contact with the latch 6, and said first-named bumper may, also like said second-named bumper, be arranged so as to require that the door be unlocked by direct application of the hand to said latch.

The bottom of the keeper 16 is arcuate like the bottom of the latch 6 and concentric therewith, so that said latch can swing without binding on the horizontal part of the bracket 7.

More or less change in the shape, size, construction, and arrangement of some or all of the parts of the door stop may be made without departing from the spirit of my invention or exceeding the scope of what is claimed.

What I claim as my invention, and desire to secure by Letters Patent, is—

1. The combination, in a door stop, with a lug carried by the door, of a swinging latch supported from a member of the door casing, and provided on the bottom with a notched keeper located normally in the path of said lug, and adapted to be swung to permit said lug and the notched part of said keeper to become engaged, when said door is opened.

2. The combination, in a door stop, with a lug carried by the door, of an arm supported from a member of the door frame, a latch pivotally connected with said arm and having on the bottom a notched keeper which is normally in the path of said lug, the construction and arrangement of parts being such that, when said door is opened, said lug encounters said keeper and causes said latch to swing to permit said lug to

pass into engagement with the notched part of said keeper.

3. The combination, in a door stop, with a lug carried by the door, of a swinging latch supported from a member of the door 70 casing, said latch having on the bottom an obliquely disposed keeper which is normally in the path of said lug, and is notched at one end to receive said lug.

4. The combination, in a door stop, with 75 a bracket attached to the door and provided with a vertical lug obliquely arranged relative to said door, of a swinging latch supported from a member of the door frame, said latch having an obliquely arranged 80 keeper which is normally in the path of said lug, and is notched at one end to receive said lug.

5. The combination, in a door stop, with a lug carried by the door, of a swinging 85 latch supported from a member of the door frame, said latch having a keeper which is normally in the path of said lug, such keeper being adapted, when encountered by said lug upon the opening of the door, to be 90 forced out of the way and then to engage said lug and prevent said door from closing, and, upon the further opening of said door, to release said lug and assume a position that enables said lug to force said 95 keeper out of the way when said door is moved to close.

6. In a door stop the combination with a latch carrying member adapted to be disposed at the top of a door frame, a freely 100 swinging gravity latch depending therefrom, and a lug to be disposed on a door for engagement with the latch; of, an ear on said latch carrying member between the latch and door frame, a spring tension member 105 to be disposed on the door for engagement with said ear to form a positive door stop, the spring tension of said member serving to maintain said latch and door lug in latched relation.

7. In a door stop the combination with a latch carrying member adapted to be disposed on a door frame at the top thereof, a freely swinging gravity latch depending therefrom, and a lug to be disposed on a 115 door for engagement with the latch; of, an ear on the latch carrying member in alignment with the latch and between said latch and the door frame, a spring tensioned positive stop member to be disposed on the door 120 for engagement with said ear, said stop member being adjustable laterally of the door and the spring tension serving to maintain said latch and door lug in latched relation.
